OXIDATION OF HYDROCARBONS TO
BORATE ESTERS

Charles N. Winnick, Teaneck, N.J., assignor to Halcon International, Inc., a corporation of Delaware
Filed July 26, 1965, Ser. No. 474,921
12 Claims. (Cl. 260—462)

This application is a continuation-in-part of copending application Serial No. 162,247, filed December 26, 1961, now abandoned, and Serial No. 202,687, filed June 15, 1962.

The present invention is concerned with the oxidation of saturated C_4 to C_8 hydrocarbons with molecular oxygen in the presence of metaboric acid or a less hydrated form of ortho boric acid including boric anhydride at conditions whereby very high oxidation selectivities and economies are achieved.

It is broadly well-known to selectively oxidize hydrocarbons such as cyclohexane to form products including cyclohexanol and cyclohexanone. In processes for the production of adipic acid, phenol, cyclohexanone, and other important chemicals, a major step in the process involves the selective oxidation of cyclohexane. A disadvantage of prior processes has been the generally low selectivity of the oxidation reaction.

It is generally old and well-known that the selectivity of molecular oxygen oxidations of hydrocarbons to a corresponding alcohol can be substantially improved by carrying out the oxidation in the presence of boric acid or a boric acid anhydride.

Luther et al., for example, in United States Patent 1,931,501 disclose that enhanced alcohol production results from the molecular oxygen oxidation of hydrocarbons, including paraffins and naphthenes, boiling above 180° C. by adding to the hydrocarbons at least 2% by weight of a weak inorganic acid such as boric acid or its anhydride.

Hellthaler et al. in United States Patent 1,947,989 disclose oxidizing hydrocarbons with molecular oxygen in the presence of boric acid whereby improved oxidation selectivity to alcohol is attained. Preferred temperatures of 160 to 200° C. for the oxidation are taught. The process is described as capable of application in all cases where hydrocarbons can be oxidized in the absence of boric acid.

Russian work by Bashkirov et al., Dokladay Aked. Nauk. SSSR. 118, No. 1, pages 149 to 152 (1958), has shown that paraffins such as tridecane can be oxidized with nitrogen-oxygen mixtures containing 3.0—3.5% oxygen at 165—170° C. with 5% added boric acid. High oxidation selectivities to alcohols and ketones is shown. A paper on the Russian work was summarized on June 3, 1959, by W. G. Toland at the Fifth World Petroleum Congress. See paper 15, section IV, "Proceeding of the Fifth World Petroleum Congress."

In addition to boric acid and anhydrides, other boron compounds have been employed. For example, French Patent 1,166,679 teaches the use of borate esters such as tributyl borate in hydrocarbon oxidations.

Although the oxidation of higher hydrocarbons, both paraffins and naphthenes, with molecular oxygen in the presence of a boron compound as above shown is indicated as proceeding readily with the production of alcohols in high selectivity, severe difficulties are encountered when it is attempted to apply this technology to lighter hydrocarbons such as hexane and cyclohexane.

It is, of course, obvious to attempt to apply this prior

2

technology to C_4 to C_8 saturated hydrocarbon oxidations. And, as expected, the oxidation selectivity can in some instances be somewhat improved when following the prior art teachings.

However, it has not heretofore been possible with the volatile C_4 to C_8 hydrocarbons to provide a molecular oxygen oxidation process having reaction selectivities comparable to those achieved with the heavier hydrocarbons while at the same time having favorable economies of operation.

For example, the Russian workers above described assert that in order to achieve high reaction selectivity it is necessary to operate with very low oxygen pressure, and in oxidation systems involving higher hydrocarbons the oxidant oxygen partial pressure can be lowered with but small reaction system changes. However, in the oxidation of the C_4 to C_8 hydrocarbons the oxygen partial pressure cannot be similarly lowered without rendering the process uneconomical and impractical. Heat input requirements necessary to maintain reaction conditions become excessive with the higher hydrocarbon systems.

Further, although prior workers have recognized that water removal is an important consideration in the oxidation of hydrocarbons such as hexane, problems associated with water removal have prevented successful application of the heavier hydrocarbon boric acid oxidation technology to lighter, more volatile hydrocarbons such as hexane.

For example, in the discussion following the presentation of the Russian paper by W. G. Toland, above referred to, at the Fifth World Petroleum Congress, H. M. Stanley of Distillers Co., Ltd., stated:

"It may well be, however, that an important limiting factor is the rate of removal of the water of esterification. So long as substantial amounts of water are present in the reaction medium, then obviously substantial proportions of free alcohols will be present and these will be susceptible to oxidation.

"If one tries to apply this process, this technique, to the lower and more volatile paraffins, this limitation becomes immediately apparent, and in fact in our laboratories, we have been unsuccessful in applying this technique to the lower paraffins, such as pentane and hexane, largely, we think, on that account."

Now, in accordance with the present invention, there is provided a novel and improved method for the molecular oxygen oxidation of saturated hydrocarbons having 4 to 8 carbon atoms.

The oxidation of this invention is carried out in a batch-wise or continuous manner by contacting gaseous molecular oxygen with a mixture of liquid hydrocarbon and meta boric acid or a less hydrated derivative at a contact temperature in the range of about 140° to 180° C. As an essential of the present invention, the reaction is so maintained that the partial pressure of water in the exit gases, i.e., the vapor above the liquid reaction mixture, in p.s.i.a., is not greater than P where P is given by the expression:

$$60 \quad (1) \quad \log_{10} P = 0.01112T - 0.259$$

and most desirably not greater than P where P is given by:

$$(2) \quad \log_{10} P = 0.0175T - 1.85$$

65 where T is the reaction temperature in degrees C.

FIGURE 1 is a graph illustrating reaction selectivity versus conversion. It also demonstrates the effect of water partial pressure on the selectivity conversion relationship. This graph represents a statistical averaging of several

hundred oxidations by means of a regression analysis. Statistical analyses have shown the curves to accurately predict true selectivities to within 1 point. Consequently, it is far more meaningful for allowing a finely accurate prediction of performance than any one or two runs where one can encounter deviations from the statistical mean values greater than 1 point.

Desirably, the oxidation of this invention is carried out in a batchwise or continuous manner by contacting gaseous molecular oxygen with a mixture of liquid hydrocarbon and meta-boric acid at a reaction temperature in the range of 140° to 180° C. During the reaction a gaseous mixture comprising water and hydrocarbon, and usually also containing inert gas such as nitrogen, is removed from the reaction zone. In this practice of the present inventive process the reaction is so maintained that the partial pressure of water in this exiting gas mixture in p.s.i.a. is not greater than P as given in Equation 1 above, preferably not greater than about 70% of P as given in Equation 1, desirably not greater than P as given in Equation 2, and most desirably 2 to 100% of P as given in Equation 2.

Through practice of the present invention, hydrocarbon oxidation reaction selectivities in excess of 80 to 85% to products from which corresponding alcohols and ketones are readily recovered can be attained with high economies of operation.

Hydrocarbons which are oxidized by the process of this invention include cyclopentane, cyclohexane, cycloheptane, cyclooctane, methyl cyclohexane, the dimethyl cyclohexanes, n-pentene, n-hexane, n-heptane, the methyl pentanes, and the like. In preferred operation, and admixture of the hydrocarbon together with a selectivity promoting amount of meta-boric acid or lower boric acid hydrate is formed. In a desirable embodiment of the invention, a slurry of ortho boric acid in the hydrocarbon is first formed. This slurry is subjected to a dehydration treatment as by passing a gas therethrough at elevated temperature to dehydrate at least part and preferably substantially all of the ortho boric acid. Other methods for producing the meta-boric acid or lower hydrate and for forming an admixture with the hydrocarbon can be used.

The meta-boric acid or lower hydrate is generally employed in amount of at least 1 mol of boron compound expressed as meta-boric acid per 6 mols of hydrocarbon oxidized. Since economic conversions are at least 4% of the hydrocarbons this corresponds to at least about 0.4% boron compound expressed as meta-boric acid by weight of the hydrocarbon-boron compound admixture. Due to problems of slurry handling in the reaction and solids separation difficulties, it is generally not desirable to employ amounts of the boron compound expressed as meta-boric acid in excess of about 20% by weight of the hydrocarbon-boron compound admixture.

Meta-boric acid is preferably employed in this invention. Included among the lower hydrates of boric acid which also can be used are boron oxide and tetra-boric acid. By "lower hydrates" is meant derivatives of ortho boric acid formed by removal of water. When lower hydrates are employed, and the partial pressure of water in the vapors over the reaction mixture is above the equilibrium pressure, the lower hydrates will tend to be converted to higher hydrates and even to meta-boric acid.

It is a feature of the present invention that generally higher hydrocarbon conversions per pass can be achieved without the selectivity decrease which accompanied such higher conversions in prior oxidation processes.

The oxidation of this invention is carried out such that about 4 to 25% desirably 8 to 20%, and preferably 10 to 15% of the hydrocarbon is oxidized per pass in a continuous system or per oxidation in a batch operation.

Suitably, the admixture of boron compound, preferably meta-boric acid, and hydrocarbon is heated to the 140° to 180° C. oxidation temperature and a gas containing molecular oxygen is passed therethrough. Although pure

oxygen can be used, it is preferred to use molecular oxygen in admixture with inert gas such as nitrogen. Concentrations of oxygen, greater or lesser than those found in air equaling 4 to 25%, can be used. It is generally preferred to employ oxygen concentrations by volume of 10% or less in the oxidant gas to avoid possible formation of explosive mixture.

During the oxidation reaction, a gaseous mixture comprising such inert gas as is in the feed oxidant stream together with any unconsumed oxygen and water and hydrocarbon vapor is continuously removed from the reaction zone. The hydrocarbon vapor may be condensed, at least partially separated from water, and returned to the reactor as a liquid. Normally, the amount of water in the reaction zone and the concentration of this water in the gases exiting from the reaction zone is substantially dependent upon the oxygen concentration in the oxidant gas stream and consumption during the reaction. However, additional possible sources of water include the feed gases, the feed hydrocarbon mixture, and reflux hydrocarbons from which a portion of the water has generally been removed by decantation, stripping or the like.

When meta-boric acid is used, the oxidation reaction is so conducted that the water partial pressure in the vapor stream leaving the liquid reaction mixture in p.s.i.a. is 0.3% to 100% of P in accordance with the expression

$$\log_{10} P = 0.01112T - 0.259$$

with T being the reaction temperature in degrees C., and preferably 0.3% to 70%.

When lower boric acid hydrates such as boron oxide are employed, pure oxygen and cooling can be employed in the reaction. It is possible to use sufficient amounts of the lower hydrate such that these hydrates react with water which is formed during the reaction or which is introduced into the reaction mixture with feed materials such that the partial pressure of water in the vapor above the reaction mixture is not greater than P as above described without the necessity of vapor removal from the reaction zone. Of course, gradations of operation are possible such that the process can be operated adiabatically or with heat input using these lower hydrates. Whereas, using meta-boric acid, as above described it is essential that the water partial pressure in the exit vapors be at least 0.3% of P, with the lower hydrates for economic operation it is necessary only that the water partial pressure in the vapor above the reaction mixture be no greater than P.

In practice of this invention wherein the hydrocarbons which are oxidized are C₄ to C₇ hydrocarbons, and the oxidation is carried out in the absence of solvent and of large amounts of lower hydrates, the process often requires positive heat input in order to insure sufficient hydrocarbon boil up and vapor removal to maintain the water partial pressure in the exit gases at a desired value within the range above designated while operating at the desired reaction temperature. The heat input can be accomplished in a variety of ways. Preferably, hydrocarbon removal from the reaction zone as vapor upon condensation and separation from water is heated and/or is vaporized and introduced into the reaction zone as vapor. Alternatively, heat can be provided through the reactor walls, by means of heating coils in the reaction zone, and the like.

With C₈ hydrocarbons, it is more often possible to operate adiabatically, in accordance with the invention. That is, the heat liberated by the reaction is about sufficient to provide the heat necessary for water and hydrocarbon vaporization.

It is possible to carry out the invention such that a solvent is employed in the reaction mixture. Suitable solvents are those which are inert during the oxidation and which can be readily separated from the reactants and reaction products. Desirably organic compounds having no reactive secondary or tertiary carbon atoms are em-

ployed. Hydrogens on primary carbon atoms are substantially inert in the present reaction. However, hydrogens on secondary and tertiary carbon atoms tend to be much more reactive in this reaction.

Preferably the compounds boil intermediate the hydrocarbon to be oxidized and the lowest boiling of the oxidation products. Illustrative solvents include hexamethyl ethane, neopentane, ethyl acetate, diteriary butyl ether, substituted benzenes, halogenated hydrocarbons and the like.

It is to be noted that the presence of a solvent will change the characteristics of the reaction system. Thus, where the solvent is higher boiling than the hydrocarbon, the reaction will be able to be carried out under more nearly adiabatic conditions and in fact cooling may be required even for the C₄ to C₇ hydrocarbons.

Successful practice of this invention requires careful control and regulation of the reaction conditions. Thus, the oxidation reaction temperature must be in the range 140° to 180° C. and preferably 160° to 170° C. In actual practice in an experimental unit an exact reaction temperature is selected; a reaction pressure is then calculated on consideration of the hydrocarbon system in the reaction (with or without solvent), the quantity of inerts fed to the reactor, and the quantity of water required to be removed, such that the volume of organics, inerts, and oxygen which may not be consumed leaving the reactor as vapor is sufficient to maintain the water pressure within the limits cited above; the heat transfer to the reactor is then adjusted so that the desired temperature and pressure conditions are met. In an alternate method of operation, the same calculation would be made, but the heat transfer could be adjusted to maintain the desired flow of organic vapors overhead, while the pressure would be adjusted to control reactor temperature. Illustrative pressures are in the range 10 to 800 p.s.i.g.

For example, in the case of the oxidation of cyclohexane using as oxidizing gas air diluted with nitrogen to a volumetric concentration of oxygen of 10%, a reaction temperature of 165° C. is preferred. At this temperature, the vapor pressure of the liquid cyclohexane is about 105 p.s.i.a.

It is desirable and important to operate at conditions of substantially complete oxygen consumption in order to make the most efficient use of the compressed oxidizing gas and to avoid explosion hazards. In the highly selective reaction of the present process, between about 1.0 and about 1.5 moles of water are formed per mol of oxygen consumed with very little carbon dioxide formation. Water contained in the feeds to the oxidation zone must likewise be removed in the manner of control of this invention. However, it is suitably illustrative to demonstrate the technique for the ideal case where there is no water in the feeds. Thus, using 10% oxygen as oxidizing gas, the water plus inerts in the oxidizing zone will be about 90 moles N₂ and 10 to 15 moles of water per 100 moles of inlet oxidizing gas.

With the above parameters, in order to control the water partial pressure in the exit gas at low level of the order of 2 p.s.i.a. the system pressure is determined by the sum of the vapor pressure of cyclohexane plus the pressure exerted by the water vapor plus inerts. For a water partial pressure of 2 p.s.i.a. for 90 percent N₂ and 10 percent water, the sum of N₂ plus water partial pressures would be 20 p.s.i.a. The system pressure then would be 20 p.s.i.a. plus the 105 p.s.i.a. cyclohexane vapor pressure, or 125 p.s.i.a. Similarly, for 85.5 percent nitrogen and 14.5 percent water (90 moles N₂-15 moles water) for a 2 p.s.i.a. water partial pressure the system pressure is 14 plus 105 or 119 p.s.i.a.

Thus, the reaction system would be operated at a pressure in the range of 119-125 p.s.i.a. with provision of sufficient heat to maintain reaction temperature and

pressure. A precise control to 2 p.s.i.a. water pressure is attained by analysis of the reactor off gases for water and appropriate pressure regulation.

In an alternate method of operation, the same calculation would be made, but the heat transfer could be adjusted to maintain the desired flow of organic vapors overhead, while the pressure would be adjusted to control reactor temperature. Illustrative pressures are in the range 10 to 800 p.s.i.g.

10 In desirable economic operation of the invention, the vapor mixture from the reaction zone is cooled to condense water and hydrocarbon. These condensed materials are separated as by decantation and the hydrocarbon returned to the reaction zone. Heat economies are achieved 15 by heat exchange between the hydrocarbon returning to the reaction zone and vapors exiting from the reaction zone; if direct contact is used for such heat exchange, further stripping of water from the returning hydrocarbon is also accomplished. Heat necessary to sustain the 20 reaction is preferably provided by heating the recycle hydrocarbon prior to introduction into the reaction zone.

At the termination of the oxidation reaction, the reaction mixture contains a substantial amount of the alkanol in the form of a borate ester thereof. If desired the borate 25 ester can be recovered as such. In order to recover the alkanol as such it is desirable to subject the oxidation reaction mixture after removal of unreacted hydrocarbon to a hydrolysis whereby the alkanol liberated can readily be recovered by distillation, for example, by adding water 30 to the oxidation reaction mixture after hydrocarbon removal and heating, e.g. to 50-150° C. Other known type techniques such as alcoholysis, transesterification, and the like can be employed.

35 Accompanying FIG. 1 demonstrates the importance of water partial pressure on oxidation selectivity over a wide conversion range. The data illustrated in FIGURE 1 were obtained by analysis of a great number of cyclohexane oxidation runs using added meta-boric acid with wide variations in operating conditions. The critical 40 effect of water partial pressure on the reaction selectivity is apparent from the figure. For example, referring to the figure, at conditions of constant conversion it is seen that reaction selectivity sharply decreases as the water partial pressure increases. At 10% conversion, for example, at 45 3 p.s.i.a. water partial pressure selectivity to cyclohexanol plus cyclohexanone is about 88% whereas at 16.8 p.s.i.a. the selectivity is about 81%.

For comparison purposes, also presented in FIGURE 50 1 is a curve showing selectivity versus conversion for cyclohexane oxidations not involving the use of boron adjuvant. The single curve is valid over a wide range of water partial pressures since water partial pressure is not an important factor effecting reaction selectivity in systems which do not employ the meta-boric acid or less 55 hydrated ortho boric acid form.

In systems not employing meta-boric acid or the like, water does not significantly influence the reaction selectivity. Water does tend to inhibit the oxidation itself, and the presence of high amounts of water has in the prior 60 art necessitated higher temperatures to overcome the inhibiting effect. However, the actual selectivity of the reaction is virtually independent of water partial pressure.

In the following examples, unless otherwise specified 65 parts and percentages are given by weight.

EXAMPLE I

Cyclohexane in amount of 2711 parts is mixed with about 450 parts of finely ground solid ortho-boric acid. The resulting slurry is heated to about 165° in an agitated, baffled, glass-lined reactor equipped with heating jacket, vapor take-off, condenser, vapor-liquid separator, water separator and reflux return line, and a nitrogen stream passed therethrough at 120 p.s.i.g. The ortho-boric acid 70 readily dehydrates substantially completely to meta-boric

acid, and a gaseous mixture of nitrogen, water vapor and cyclohexane is removed. Cyclohexane is condensed from the vapor, separated from water and returned to the reactor.

The resulting slurry of meta-boric acid in cyclohexane is maintained at 165° C. by adjusting the heat supply to the jacket as required. A gaseous mixture of 4% by volume oxygen in nitrogen is introduced into the reactor below the liquid surface at a rate of about 4 volumes per minute (1 atm. and 25° C.) per about 3.8 volumes of slurry. Oxygen absorption is substantially complete after a short period of time. The pressure in the reaction zone is maintained at 120 p.s.i.g. (134.7 p.s.i.a.) by means of a pressure control valve on the vapors leaving the vapor-liquid separator. At these reaction conditions, the oxygen partial pressure at the point of entry into the reaction zone is about 1.2 p.s.i.a. taking into consideration the cyclohexane vapor pressure of 105 p.s.i.a. at the reaction temperature (i.e.: 4% of 134.7-105).

During the reaction a vapor mixture comprising cyclohexane, water and nitrogen is continuously removed from the reaction zone and cooled to condense water and cyclohexane. Vapors are separated from condensate in the separator. After separation from water by decantation the liquid cyclohexane is recycled to the reactor. Under the above reaction conditions, the water partial pressure in the gases exiting from the reaction zone is about 1.6 p.s.i.a.

After completion of the reaction (about 6 hours), the reaction mixture is admixed with 200 parts of water and agitated under reflux of water-hydrocarbon azeotrope (about 70° C.) for 1 hour to hydrolyze borate esters. The resulting mixture is filtered to separate solid ortho-boric acid and the filtrate is decanted to separate an organic phase from an aqueous phase. The aqueous phase is extracted with a small amount of cyclohexane and the extract is combined with the organic phase. The organic phase is extracted with a small amount of water to remove ortho-boric acid. The resulting extracted organic mixture is distilled to separate cyclohexane overhead from a bottoms cyclohexanol fraction. The cyclohexanol fraction in the amount of 360 parts contains about 82% cyclohexanol and 3% cyclohexanone, and the remainder other oxygenated cyclohexane products. The cyclohexane conversion is about 11%.

EXAMPLE II

In another comparative example, the importance of maintaining the temperature within the specified 140° C. to 180° C. range is illustrated.

Example I is repeated except that a slurry of 100 parts of ortho-boric acid in 1000 parts of cyclohexane is dehydrated and the resulting mixture of meta boric acid and cyclohexane is oxidized for 4 hours at 200° C. and 253 p.s.i.a. Oxidant gas comprising by volume 4% oxygen in nitrogen is contacted with the cyclohexane mixture at a rate of 137 volumes per hour per 1.4 volumes of slurry, and the water partial pressure in the effluent gas was less than 3 p.s.i.a.

The reaction mixture is worked up as above described and shows a reaction selectivity to cyclohexanol and cyclohexanone of about 75.7% at cyclohexane conversion level of about 6%. These data clearly demonstrate the importance of maintaining oxidation temperature not greater than about 180° C. in order to achieve the desirable high reaction selectivity of the present invention.

EXAMPLE III

As further comparison, illustrating operation which is not within the scope of the present inventive process, a slurry of 900 parts of cyclohexane and 231 parts of boron oxide is formed. About 100 p.p.m. of cobalt based on cyclohexane is added as cobalt naphthenate.

Air is passed through this slurry at a rate of about 170 volumes per hour per 1.3 volumes of slurry. The

reaction is carried out at a temperature of 190° C. and at a pressure of 200 p.s.i.g. Oxygen absorption after 55 minutes' reaction time is about 32 volumes.

The reaction mixture is worked up as described in Example I. About 12% of the cyclohexane is converted within reaction selectivity to cyclohexanol of 67.6% and a selectivity to cyclohexanone of 3.9%.

The total selectivity to cyclohexanol and cyclohexanone of 71.5% illustrates that by the process of this example little or no selectivity improvement is achieved as contrasted with cyclohexane operation not employing a boron compound.

EXAMPLE IV

As a further comparison, it is attempted to carry out the oxidation as described in Example I at a temperature of 130° C. No reaction is obtained. This example illustrates the importance of the lower specified temperature of the present invention.

An admixture of 66 parts of finely ground ortho-boric acid in 660 parts of n-hexane is dehydrated and oxidized as described in Example I. The reaction temperature is 165° C., and reaction pressure 170 p.s.i.g. Oxidant gas consisting of 4% oxygen in nitrogen is employed at a rate of about 137 volumes per hour per volume of slurry. Inlet oxygen partial pressure is about 1.7 p.s.i.a. and exit gas water partial pressure is about 2.2 p.s.i.a. Oxidation is 4 hours, heat input by means of vaporized recycle hexane is maintained sufficient to provide for water removal at the rate at which it is formed in and introduced into the reaction zone.

After working up as in Example I, at 7% hexane conversion the selectivity to alcohol plus ketone is 86%.

EXAMPLE V

An admixture comprising a slurry of 100 parts of meta boric acid in 1000 parts of methyl cyclohexane is oxidized in a manner similar to that described in Example I. The reaction temperature is 160° C. and the reaction pressure is 62 p.s.i.g. Oxidant gas consisting of 8% oxygen in nitrogen is employed at a rate of about 170 volumes per hour per 1.3 volumes of slurry. The oxidation is continued until 24 liters of oxygen is absorbed.

The inlet oxygen partial pressure is about 1.34 p.s.i.a. and the exit gas water partial pressure is about 1.74 p.s.i.a. Heat input by means of vaporized recycle methyl cyclohexane is maintained sufficient to provide for water removal at the rate at which it is formed in and introduced into the reaction zone. About 10% of the methyl cyclohexane is reacted.

After working up as in Example I, the overall selectivity to alcohol plus ketone is about 78%. 1-methyl cyclohexanol is formed in amount of about 26%, 2-methyl cyclohexanol is formed in amount of about 17%, 3- and 4-methyl cyclohexanols together are formed in amount of about 28%, and a mixture of methyl cyclohexanones in amount of about 6% is formed.

EXAMPLE VII

Example V is repeated substituting n-heptane in place of the methyl cyclohexane. Generally similar selectivity to alcohol plus ketone are obtained.

EXAMPLE VIII

A series of runs designated as A, B, C and E in the following table were made in accordance with this invention. In Runs A, B and E boric acid (which rapidly dehydrated to meta boric acid during the reaction) was employed. Boric oxide was employed in Run C.

In each case the boron compound was admixed with cyclohexane in the indicated amount. Cyclohexanone in the amounts indicated was added to the reaction mixture as oxidation initiator. Air was continuously passed through the reaction mixture at the specified rate.

A glass line reactor equipped with a vapor take-off, condenser and water separator was used. During the reaction, vapors were continuously removed, condensed, water separated and the cyclohexane returned to the reaction.

At the termination of the reaction, the resulting mixture was distilled to separate unreacted cyclohexane, and the thusly obtained oxidation reaction mixture was hydrolyzed. The hydrolysis was accomplished by adding water and heating to about 80-100° C. The cyclohexanol-cyclohexanone product was recovered by decantation and steam distillation.

The following table shows the results obtained. Run D wherein no boron compound was used is included for purpose of comparison.

Table I

	Run				
	A	B	C	D	E
Cyclohexane, parts	2,711	2,684	2,740	2,600	2,759
Boron compound, parts	303	154	84	None	456
Cyclohexanone, parts	5	5	5	None	None

Reaction pressure, p.s.i.g	120	125	150	150	120
O ₂ Uptake (approx.) liters	54	51	74		50
Cyclohexane reacted, percent	7.6	7.8	6.7	8.3	14.4
Reaction Selectivity to cyclohexanol and cyclohexanone, percent	80	76	80	61	90
Ratio cyclohexanol/cyclohexanone	19.3/1	4.7/1	3.9/1	1.2/1	31/1
Water partial pressure in effluent gas, p.s.i.a	2.5-4.2	8.5-9.0	9.4-12.7	17.80-18.0	1.1-1.3

¹ 4% oxygen in nitrogen.

The above results show the improved oxidation selectivity to cycloalkanol and cycloalkanone obtained through the use of the specified boron compounds. The results also establish the very high selectivity to cycloalkanol attained through the use of the higher amounts of boron compounds. For example, in Runs A and E selectivities to cyclohexanol and cyclohexanone were obtained which were about 130 to 150% that obtained where no boron compound was employed (Run D). Many fold improvements in selectivity to cyclohexanol were attained as shown in the above data.

EXAMPLE IX

Runs A, B, C and E of Example VIII were repeated using cyclooctane instead of cyclohexane. Substantially similar percentage improvements in reaction selectivity to cyclooctanol and cyclooctanone and in the cyclooctanol to cyclooctanone ratio were obtained as contrasted with operation employing no boron compound.

EXAMPLE X

Runs A, B, C and E of Example VIII were repeated using cyclopentane instead of cyclohexane. Substantially similar percentage improvements in reaction selectivity to cyclopentanol and cyclopentanone and in the cyclopentanol to cyclopentanone ratio were obtained as contrasted with operation employing no boron compound.

EXAMPLE XI

Runs A, B, C and E of Example VIII were repeated using cycloheptane instead of cyclohexane. Substantially similar percentage improvements in reaction selectivity to cycloheptanol and cycloheptanone and in the cycloheptanol to cycloheptanone ratio were obtained as contrasted with operation employing no boron compound.

EXAMPLE XII

Methylcyclohexane was oxidized in accordance with the invention in a manner similar to that described in Example VIII, Run E. The following table shows reaction conditions and the results obtained. A run without the use of boron compound is presented for purposes of comparison.

10
Table II

EXAMPLE XIII

Example I is repeated except that a gaseous mixture of 15 10% by volume oxygen in nitrogen is employed. The

reaction zone pressure is maintained at about 259 p.s.i.a. At the reaction conditions, the oxygen partial pressure at the point of entry into the reaction zone is about 15.4 p.s.i.a. taking into consideration the cyclohexane vapor pressure of 105 p.s.i.a. at the 165° C. reaction temperature (e.g., 10% of 259-105). Vapors are removed as described in Example I. Under these reaction conditions, the water partial pressure in the gases exiting from the reaction zone is about 20 p.s.i.a.

The reaction is continued until about 10.5% of the cyclohexane is reacted. The reaction mixture is worked up as described in Example I. Molar selectivity to cyclohexanol plus cyclohexanone is found to be 80%, with a ratio of cyclohexanol to cyclohexanone of about 6:1.

EXAMPLE XIV

Example I is repeated except that a gaseous mixture of 50 10% by volume oxygen in nitrogen is employed. The reaction zone pressure is maintained at about 336 p.s.i.a. At the reaction conditions, the oxygen partial pressure at the point of entry into the reaction zone is about 23 p.s.i.a. taking into consideration the cyclohexane vapor pressure of 105 p.s.i.a. at the 165° C. reaction temperature (i.e., 10% of 336-105). Vapors are removed as described in Example I. Under these reaction conditions, the water partial pressure in the gases exiting from the reaction zone is about 30 p.s.i.a.

60 The reaction is continued until about 9.0% of the cyclohexane is reacted. The reaction mixture is worked up as described in Example I. Molar selectivity to cyclohexanol plus cyclohexanone is found to be 80%.

The present inventive process can be carried out with 65 out a catalyst. In previous processes which did not employ a boron compound, it was necessary to employ small amounts of a catalytic material such as cobalt salt in order to successfully oxidize cyclohexane with molecular oxygen to a mixture which comprised cyclohexanone and cyclohexanol. However, in the present process wherein molecular oxygen is contacted with the mixture of meta-boric acid and hydrocarbons under the stated conditions, it has been found that materials previously used as catalysts in non-boric acid oxidations have substantially no effect or 70 possibly an adverse effect and thus are not required.

Initiators such as aldehydes, ketones, and peroxides can be used. Illustrative of such initiator is cyclohexanone, hydrogen peroxide, tertiary butyl hydroperoxide, and the like.

EXAMPLE XV

Cyclohexane is continuously oxidized in a series of four reactors at a temperature of 165° C. and a pressure of 140 p.s.i.a. using as oxidizing gas 10 vol. percent O₂ and 90 vol. percent N₂.

To the first reactor is added per hour 2750 mols of liquid commercial purity cyclohexane and 67 mols metaphoric acid preheated to about 165° C. Also introduced into the first reactor per hour are 440 mols of cyclohexane vapor at about 165° C. and 240 moles of said oxidizing gas.

A vapor mixture of about 770 moles cyclohexane, 207 moles N₂, 2 moles unreacted O₂, and about 25 moles water per hour is removed from the first reactor.

A liquid stream containing about 2395 moles cyclohexane and about 25 moles oxidized cyclohexane is continuously passed from the first to the second reactor. About 350 moles cyclohexane vapor at about 165° C. and 210 moles of oxidizing gas were introduced into the second reactor.

A vapor mixture of about 680 moles cyclohexane, 189 moles nitrogen and 25 moles water was removed per hour from the second reactor. A liquid mixture containing about 2040 moles cyclohexane and 50 moles oxidized cyclohexane was transferred per hour from the second to the third reactor.

About 330 mol cyclohexane vapor at about 165° C. and 210 moles oxidizing gas were introduced per hour into said third reactor and contacted with the liquid mixture.

From the third reactor there was withdrawn per hour a vapor mixture of about 660 moles cyclohexane, 189 moles nitrogen and 25 moles water and also a liquid mixture containing about 1685 moles cyclohexane and 75 moles oxidized cyclohexane which was sent to the fourth reactor.

About 290 moles cyclohexane vapor at about 165° C. and 210 moles oxidizing gas per hour were introduced into the fourth reactor per hour.

A vapor mixture of about 620 moles cyclohexane, 189 moles nitrogen, and 25 moles water were removed per hour from the fourth reactor. A liquid product mixture of 1330 moles cyclohexane and 100 moles oxidized product were recovered per hour.

The vapor streams from the reactor were condensed and cyclohexane recovered and recycled after separation of water contained therein.

The product mixture was hydrolyzed as described in Example I and the organic phase distilled to separate cyclohexane which was recycled to the reaction.

The product fraction was about 88% cyclohexanol and cyclohexanone at a cyclohexane conversion of 7%. The cyclohexanol to cyclohexanone ratio was about 10:1.

The water partial pressure in the effluent having each of the four reactors is maintained at a low level. The first reactor effluent partial pressure is $\frac{25}{1004}(140) = 3.5$ p.s.i.a. That of the second reactor is $\frac{25}{894}(140) = 3.9$ p.s.i.a. For the third reactor the water partial pressure is $\frac{25}{874}(140) = 4.0$ p.s.i.a., and for the fourth reactor $\frac{25}{834}(140) = 4.5$ p.s.i.a.

EXAMPLE XVI

For comparison purposes a run was made oxidizing cyclohexane with air with 6.2% by weight ortho-boric acid and controlling the water partial pressure in excess of about 100 p.s.i.a. The temperature was 165°-170° C. and pressure was 500 p.s.i.g. At 12.7% cyclohexane conversion, the selectivity to cyclohexanol plus cyclohexanone was only about 64%.

This comparison clearly demonstrates that operation outside the scope of the invention at high water partial

pressure results in poor selectivities of the order of those obtained with boron compound addition.

By selectivity in the foregoing is meant the molar percentage of reacted hydrocarbon which forms the alcohol or ketone. By conversion is meant the percentage of hydrocarbon changed which is reacted.

What is claimed is:

1. The process for the oxidation of a C₄ to C₈, saturated hydrocarbon to produce a borate ester containing oxidation reaction mixture wherein a molecular oxygen containing gas is contacted in a reaction zone with a mixture of said hydrocarbon in the liquid phase and a lower hydrate of boric acid, comprising the combination of effecting said contact at a reaction temperature in the reaction zone in the range of 140° to 180° C., removing a gaseous mixture comprising vapors of said hydrocarbons and water from said liquid phase during the oxidation, and maintaining the partial pressure of water in p.s.i. in said gaseous mixture not greater than P where P is given by the equation:

$$\log_{10} P = -1.85 + 0.0175(T)$$

with T being the reaction temperature in degrees C., and recovering the resulting oxidation reaction mixture.

2. The process for the oxidation of a C₄ to C₈, saturated hydrocarbon to produce a borate ester containing oxidation reaction mixture wherein a molecular oxygen containing gas is contacted in a reaction zone with a mixture of said hydrocarbon in the liquid phase and meta boric acid, comprising the combination of effecting said contact at a reaction temperature in the reaction zone in the range of 140° to 180° C., removing a gaseous mixture comprising vapors of said hydrocarbon and water from said liquid phase during the oxidation, and maintaining the partial pressure of water in p.s.i. in said gaseous mixture leaving the said liquid phase in the range 2% to 100% of P where P is given by the equation:

$$\log_{10} P = -1.85 + 0.0175(T)$$

with T being the reaction temperature in degrees C., and recovering the resulting oxidation reaction mixture.

3. The process of claim 2 wherein said hydrocarbon is cyclohexane.

4. The process of claim 2 wherein said hydrocarbon is n-hexane.

45 5. The process of claim 2 wherein said hydrocarbon is methyl cyclohexane.

60 6. The process for the oxidation of a C₄ to C₇ saturated hydrocarbon to produce a borate ester containing oxidation reaction mixture wherein a molecular oxygen containing gas is contacted in a reaction zone with a mixture of said hydrocarbon in the liquid phase, and meta boric acid, comprising the combination of effecting said contact at a reaction temperature in the reaction zone in the range of 140° to 180° C., continuously during the oxidation removing a gaseous mixture from said liquid phase comprising vapors of said hydrocarbon and water, continuously providing heat to said reaction zone in addition to the heat of reaction, and maintaining the partial pressure of water in p.s.i. in said gaseous mixture leaving the said liquid phase in the range 2% to 100% of P wherein P is given by the equation:

$$\log_{10} P = -1.85 + 0.0175(T)$$

65 with T being the reaction temperature in degrees C., and recovering the resulting oxidation reaction mixture.

70 7. The process for the oxidation of cyclohexane wherein a molecular oxygen containing gas is contacted with a mixture of cyclohexane in the liquid phase and meta boric acid to produce a borate ester reaction mixture comprising the combination of effecting said contact at a reaction temperature in the reaction zone in the range of 140° to 180° C. continuing the contact until 4% to 25% of the cyclohexane is reacted, continuously during said contact removing a gaseous mixture containing vapors of said cyclohexane and water from said liquid phase condensing the

thus removed cyclohexane and water, separating the condensed cyclohexane, vaporizing separated cyclohexane, returning the vaporized cyclohexane into contact with the liquid mixture in the reaction zone, and maintaining the partial pressure of water in p.s.i. in the gaseous mixture leaving the liquid phase in the range 2% to 100% of P wherein P is given by the equation:

$$\log_{10} P = -1.85 + 0.0175(T)$$

with T being the reaction temperature in degrees C., and recovering the resulting oxidation reaction mixture.

8. The process of claim 7 wherein 8% to 20% of the cyclohexane is reacted.

9. The process for the oxidation of a C₄ to C₈, saturated hydrocarbon to produce a borate ester containing oxidation reaction mixture wherein a molecular oxygen containing gas is contacted in a reaction zone with a mixture of said hydrocarbon in the liquid phase and a lower hydrate of boric acid, comprising the combination of effecting said contact at a reaction temperature in the reaction zone in the range of 140° to 180° C., removing a gaseous mixture comprising vapors of said hydrocarbons and water from said liquid phase during the oxidation, and maintaining the partial pressure of water in p.s.i. in said gaseous mixture not greater than P where P is given by the equation:

$$\log_{10} P = 0.01112T - 0.259$$

with T being the reaction temperature in degrees C., and recovering the resulting oxidation reaction mixture.

10. The process for the oxidation of a C₄ to C₈, saturated hydrocarbon to produce a borate ester containing oxidation reaction mixture wherein a molecular oxygen containing gas is contacted in a reaction zone with a mixture of said hydrocarbon in the liquid phase and meta boric acid, comprising the combination of affecting said contact at a reaction temperature in the reaction zone in the range of 140° to 180° C., removing a gaseous mixture comprising vapors of said hydrocarbon and water from said liquid phase during the oxidation, and maintaining the partial pressure of water in p.s.i. in said gaseous mixture leaving the said liquid phase not greater than P where P is given by the equation:

$$\log_{10} P = 0.01112T - 0.259$$

with T being the reaction temperature in degrees C., and recovering the resulting oxidation reaction mixture.

11. The process for the oxidation of a C₄ to C₇ saturated hydrocarbon to produce a borate ester containing oxidation reaction mixture wherein a molecular oxygen containing gas is contacted in a reaction zone with a mixture of said hydrocarbon in the liquid phase, and meta boric acid, comprising the combination of effecting said contact at a reaction temperature in the range of 140° to 180° C., continuously during the oxidation removing a gaseous mixture from said liquid phase comprising vapors of said hydrocarbon and water, continuously providing heat to said reaction zone in addition to the heat of reaction, and maintaining the partial pressure of water in p.s.i. in said gaseous mixture leaving the said liquid phase not greater than P where P is given by the equation:

$$\log_{10} P = 0.01112T - 0.259$$

with T being the reaction temperature in degrees C. and recovering the resulting oxidation reaction mixture.

12. The process for the oxidation of cyclohexane wherein a molecular oxygen containing gas is contacted with a mixture of cyclohexane in the liquid phase and meta boric acid to produce a borate ester reaction mixture comprising the combination of effecting said contact at a reaction temperature in the reaction zone in the range of 140° to 180° C. continuing the contact until 4% to 25% of the cyclohexane is reacted, continuously during said contact removing a gaseous mixture containing vapors of said cyclohexane and water from said liquid phase condensing the thus removed cyclohexane and water, separating the condensed cyclohexane, vaporizing separated cyclohexane, returning the vaporized cyclohexane into contact with the liquid mixture in the reaction zone, and maintaining the partial pressure of water p.s.i. in the gaseous mixture leaving the liquid phase not greater than P where P is given by the equation:

$$\log_{10} P = 0.01112T - 0.259$$

with T being the reaction temperature in degrees C., and recovering the resulting oxidation reaction mixture.
